MULTISECTION CRANKSHAFT

Francis Gerard Lake, New York, N. Y., assignor to
The M. W. Kellogg Company, New York, N. Y.,
a corporation of Delaware

Application June 10, 1947, Serial No. 753,601

8 Claims. (Cl. 139—1)

1

The present invention relates to cloth weaving looms, and more particularly to the means by which certain operating parts of the loom are mounted and supported.

The conventional type of loom comprises a main crank shaft having two double cranks integral therewith mounted near the respective loomsides for angularly oscillating the swords by which the lay is reciprocated. Since the main crank shaft and the double cranks constitute one solid piece, split plain bearings only may be used as supports. Even with split bearings, the assembly of the shaft and its cranks in the loomsides is a difficult and time consuming operation.

One object of the present invention is to provide new and improved main crank shaft and supports therefor, which lend themselves to easy and expeditious assembly, and which permit the use of non-split, preferably anti-friction, shaft bearings of the unit type.

As a feature of the present invention, the crank shaft is divided into at least three separate sections, comprising two end sections having respective double crank conformations, and one, or more, straight intermediate sections coupled to said end sections. The shaft parts of the end sections beyond the double cranks are straight, thereby permitting non-split, anti-friction bearing units or non-split plain bearing units, to be slipped on to said shaft parts for mounting purposes, before the intermediate section, or sections, is coupled into position.

As a further feature, each of the loomsides comprises a pair of spaced substantially vertical frame webs carrying shaft supporting structures with respective openings to receive the shaft parts of the end crank shaft sections, and to mount the bearings for said shaft parts. These openings extend to the top of shaft supporting structure to permit said end crank shaft sections to be lowered into position into said openings with each double crank between the webs of each corresponding loomside. The openings are of key-hole conformation, so that after the end crank shaft sections are lowered into said openings, the non-split bearing units, anti-friction or plain, on the shaft parts of said sections beyond the double cranks are slid along said shaft parts, and into said openings, and are locked therein against movement transverse to the axis thereof, thereby correspondingly locking said end crank shaft sections against transverse withdrawal from said openings. With the two end crank shaft sections supported in position, the intermediate shaft section, or sections, may be slipped into position therebetween and connected thereto.

As a still further feature of the invention, the crank shaft components are preferably connected together by means of couplings which provide maximum torsional rigidity while they permit a

2

sufficient degree of axial misalignment of the connected shaft parts to make it possible to secure a sufficiently rigid and stable operating structure while facilitating its assembly.

5. Various other objects, features and advantages of the invention will be apparent from the following particular description, and from an inspection of the accompanying drawings, in which—
10. Fig. 1 is a front view of the portion of the loom embodying the present invention, and shows the frame and the sectional main crank shaft supported in position in said frame;
15. Fig. 2 is a front view of the left-hand portion of the loom, and shows the left-hand end section of the crank shaft in raised position with respect to the left-hand loomside, and about to be lowered in position with respect to said loomside;
20. Fig. 3 is a side elevation of the inner frame of the left loomside shown in Fig. 2, and shows the key opening in said frame for receiving a portion of the left-hand end section of the crank shaft and its bearing housing;
25. Fig. 4 is a fragmentary front view of the left-hand portion of the loom, and shows the left-hand end section of the crank shaft and a non-split bearing therefor in mounted position with respect to the left loomside;
30. Fig. 5 is a front view of the right-hand portion of the loom partly exploded, and shows the right-hand end section of the crank shaft in raised position with respect to the right loomside and about to be lowered in position with respect to said loomside;
35. Fig. 6 is a side elevation of the inner frame of the right loomside shown in Fig. 5, and shows the key opening in said frame for receiving a portion of the right-hand end section of the crank shaft and its bearing housing; and

40. Fig. 7 is a side elevation of the bearing supporting structure for the outer end of the right-hand end section of the crank shaft.

In the following description, the left-hand side of the loom is at the left-hand of an operator facing the loom, and the front of the loom is the portion of the loom nearest to the operator.

Referring to the drawings, the loom as shown in Fig. 1 comprises a frame 10 having a left-hand loomside 11 and a right-hand loomside 12 interconnected at the bottom by girts 13, and at the top by an arch 14 adapted to support the harness rolls.

45. The loomsides 11 and 12 are identical in shape, but are provided with different shaped openings for receiving the various mechanisms. The left-hand loomside 11 comprises two spaced parallel vertical webs 15 and 16 connected and braced by plates 17 in a manner indicated in copending application Serial No. 691,237. The right-hand

loom side 12 also comprises two spaced parallel vertical webs 18 and 19 connected and braced by plates 20, as indicated in said copending application.

Supported in the frame structure described is a crank shaft 25, from which the swords (not shown) are angularly oscillated to reciprocate the lay (not shown) and from which other mechanisms of the loom, such as the pick cam shafts 26 and 27 are operated. As a feature of the present invention, the crank shaft 25 is made of two crank end sections 28 and 29, and one, or more, intermediate straight shaft sections 30 coupled to said crank end sections. For simplicity's sake only one intermediate section 30 is shown. The right-hand crank end section 28 made of one piece comprises a double crank 31, a short inner shaft part 32 on one side thereof, and a longer outer shaft part 33 on the other side. The double crank 31 is located between the two frame webs 18 and 19, and the shaft parts 32 and 33 extend through respective openings in said web in a manner to be described.

The short shaft part 32 is supported in bearing 34 secured to the frame web 19 in a manner to be described. The bearing 34 is a non-split bearing unit. While the non-split bearing unit may be of the plain type, it is preferably of the anti-friction type employing balls, rollers, etc. A non-split bearing unit may advantageously be used in the novel construction since such bearing unit may easily be slipped axially on or off the shaft part 32.

The longer outer shaft part 33 projects beyond the outer side of the frame 12, and is supported at its inner end in bearing 35, which like bearing 34 is a non-split bearing unit of the anti-friction type, secured to the frame web 18 in a manner to be described. The bearing 35 is mounted as a unit on the shaft part 33, and can be axially slipped on or slipped off said shaft part. The shaft part 33 carries a gear 36 meshing with a gear 37 on the pick cam shaft 26, supported by non-split anti-friction bearing units 38 in the frame webs 18 and 19. The shaft part 33 also carries a pulley 40 mounted for rotation thereon, a clutch 41 for coupling the pulley 40 to the shaft part or disengaging it therefrom, and a hand wheel 43 for manual rotation of the crank shaft 25 when said pulley is disengaged from said shaft parts. The clutch 41 is shifted by a device 47 controlled manually or automatically or both, in any well-known manner.

At its outer end, the shaft part 33 is supported in a non-split anti-friction bearing 48 mounted, as will be described, as a unit on a frame piece 49 secured to the frame 12.

The left-hand crank shaft section 29 is also made of one piece, and comprises a double crank 50, a short inner shaft part 51 on one side thereof, and a longer outer shaft part 52 on the other side. The double crank 50 is located between the two frame webs 15 and 16, and the shaft parts 51 and 52 extend through respective openings in said webs in a manner to be described.

The short shaft part 51 is supported in a bearing 54, which like bearing 34 is a non-split bearing unit of the anti-friction type, secured to the frame web 15 in a manner to be described. The bearing 54 is mounted as a unit on the shaft part 51 and can be axially slipped on or slipped off said shaft part.

The longer shaft part 52 carries a gear 57 meshing with a gear 58 on the pick cam shaft 27 supported by non-split anti-friction bearing

units 60 in the frame webs 15 and 16. The shaft part 52 also carries a brake unit 61 operable for loom shut-downs in a manner well-known in the art.

The intermediate shaft section 30 which is of the floating type is straight, and is connected at its ends to the ends of the short shaft parts 32 and 51 by means of flexible couplings 63 and 64. These couplings are desirably of the type that provides maximum torsional rigidity while it allows a substantial axial misalignment of the coupled shafts. The couplings 63 and 64 will not be described in detail here as they are readily available articles of commerce. Each of the couplings consists of two flanged sleeves or hubs, each keyed to the end of one of the two shafts to be connected.

To facilitate assembly, each of the frame webs 15, 16, 18 and 19 has an aperture 65 opened at its upper end to afford free shaft ingress therein. Secured to each of these frame webs across its aperture 65 by spot welding or the like is a bearing mounting plate 66 or 66a provided with a keyhole 67 for centering the bearing unit and locking it against transverse movement, and having its outer surface desirably machine finished to assure accuracy in the mounting of the bearing units. The keyhole 67 has a circular base 68 extending for more than 180°, and is opened at the top by a restricted neck part 70 wide enough to permit the crank shaft parts 32, 33, 51 and 52 to pass freely therethrough. At its upper end 71, the neck 70 of the keyhole 67 is flared to facilitate entry of the crank shaft parts thereinto.

Mounting plates 66 of similar sizes and shapes are provided for the bearing units 34, 35 and 54 respectively, and a mounting plate 66a is provided for the bearing unit 55, larger in size to accommodate a frame 69 by which the brake unit 61 is fixed to the loomside 11, but otherwise similar to said bearing plates 66.

Each of the bearing units 34, 35, 54 and 55 has an end mounting flange 75 with an axial key extension 76 of reduced diameter conforming substantially with the diameter of the circular base 68 of the keyhole 67, so as to fit snugly therein.

For mounting the bearing units 34, 35, 54 and 55 on to the mounting plates 66 and 66a and to the frame webs 15, 16, 18 and 19, each of said plates has a series of bolt holes 77 registering with holes in said frame webs and adapted to receive bolts 78 carried by the mounting flanges 75 of said bearing units.

The frame piece 49 for supporting the bearing unit 48 for the outer end of the crank shaft part 33 comprises a curved channel arm 80 secured at one end to the lower end of the frame web 18, as for example, by bolting, and a channel yoke 81 secured intermediate its ends to the other end of said arm. The yoke 81 extends horizontally around the crank shaft part 33 and the devices carried thereby, and is secured at its ends to the upper end of the frame web 13, as for example, by bolting.

For supporting the bearing unit 48 in the frame piece 49, said frame piece is formed at the intersection of the arm 80 and yoke 81 with a bearing mounting structure 83 defining a key-hole 84 similar to the keyhole 67 of the bearing mounting plates 66, and having a circular base 85 to receive snugly the circular housing 86 of the bearing unit 48 and a neck 87 wide enough 75 and opened at its upper end to permit free in-

gress of the outer end of the crank shaft part 33, therethrough. The bearing unit 48 has a flange 90 by which said unit can be secured by bolts or studs to the bearing mounting structure 83.

Since the devices 36, 40, 41 and 43 may be axially slipped off or on the crank shaft part 33, and the devices 57 and 61 may be similarly slipped axially off or on the crank shaft part 52, the bearings 35 and 55 may be axially slipped on these crank shaft parts as units, while said devices are off said crank shaft parts.

In the assembling of the loom parts described, the crank shaft section 28 with the devices 36, 40, 41 and 43 attached in position, and the bearing units 34 and 35 supported thereon, but axially slipped away from each other to clear the bearing mounting plates 66, is lowered from the elevated position shown in Fig. 5 to cause the shaft parts 32 and 33 to pass into the respective key-holes 67 of said plates, and to cause the outer end of the shaft part 33 to pass into the keyhole 84 of the bearing mounting structure 83. After the shaft parts 32 and 33 are centered in the circular bases 68 of the keyholes 67 in the bearing mounting plates 66 and 66a, the bearing units 34 and 35 are slid along their respective shaft parts into said circular keyhole bases, and the bearing unit 48 is slid into the circular base 85 of the keyhole 84 in the end bearing mounting structure 83. All necessary bolting or fastening of the different bearing units of the left loom side may then be effected.

The crank shaft section 29 with the devices 57 and 61 attached in position thereon and the bearing units 54 and 55 slid axially back, may be similarly lowered from an elevated position shown in Fig. 2. When the shaft section 29 has been properly centered with respect to the keyholes 67, said bearing units are then slid into their respective keyholes as indicated in Fig. 4, and all necessary bolting or fastening of the different bearing units of the right loom side may be effected.

The center shaft section 30 is then positioned between the crank shaft sections 28 and 29, and the couplings 63 and 64 bolted.

It is to be noted that by reason of the novel multipiece crank shaft arrangement, each loom side may be assembled independently of the other side in a simple and efficient manner. It is also to be noted that by reason of the flexible couplings employed it is not necessary to align all of the bearings of the shaft assembly; only those of each loom side need be aligned as the flexible couplings take care of misalignment between assemblies that may result in ordinary assembly when proper procedure and skilled workmen are employed.

While the invention has been described with particular reference to a specific embodiment, it is to be understood that it is not to be limited thereto, but is to be construed broadly and restricted solely by the scope of the appended claims.

What is claimed is:

What is claimed is:

1. In a loom, a pair of loomsides having openings adjacent their upper ends, a frame piece connected to one of said loomsides on the outer side of said latter loomside, and defining an additional opening substantially at the same level as said loomside openings said loomsides and said frame piece being cut away from their upper ends to permit shaft ingress into said openings, a crank shaft for operating the lay oscillating

swords extending across said loomsides and in said openings, and bearings for said shaft supported in said loomsides and said frame piece and centered in said openings.

5. 2. In a loom, the combination as described in
claim 1, said frame piece comprising an arm ex-
tending upwardly from said loomside, a yoke se-
cured to the upper end of said arm and extend-
ing substantially horizontally around the end of
10: said shaft, and a bearing mounting structure at
the intersection of said yoke and said arm de-
fining said additional opening.

3. In a loom, the combination as described in
claim 1, said crank shaft being of sectionalized
15: construction to permit the easy assembly and
mounting thereof, each of said openings having
a circular base of more than 180° and a neck of
reduced width extending upwardly of said struc-
20: ture to permit shaft ingress therein, said bear-
ings being of the non-split unit type and adapted
to be slid axially along the shaft parts of said
crank shaft into respective openings for as-
sembly, and being of a size to permit them to be
received snugly in respective openings.

25: 4. In a loom; a frame structure comprising
spaced loomsides having bearing receiving open-
ings adjacent their upper ends, each of said loom-
sides being cut away from its upper end to said
openings to provide passageways for shaft and
30: bearing ingress into said openings, a crank shaft
unit for operating the lay swords extending in
said openings crosswise of said loomsides and
comprising two crank end sections and an inter-
mediate straight section coupled thereto and
35: bearings for said shaft supported on said loom-
sides and centered in said openings, said crank
shaft unit being adapted to be assembled exter-
nally of said frame structure and moved into po-
40: sition in said openings through said passage-
ways.

5. In a loom, a frame structure comprising
spaced loomsides, each provided with a con-
tinuous upper portion and having bearing receiv-
ing openings in said continuous upper portion,
45: each of said loomsides being cut away from its
upper end to said bearing receiving openings to
provide passageways for shaft and bearing ingress
into said openings, a crank shaft unit for oper-
ating the lay swords of the loom extending in said
50: openings crosswise of said loomsides and com-
prising two crank end sections and an inter-
mediate straight section coupled thereto and
bearings for said shaft supported on said loom-
sides and centered in said openings, said crank
55: shaft unit being adapted to be inserted into and
removed from said openings as a unit through
said passageways.

6. In a loom, a frame structure comprising a
pair of spaced loomsides each made up of a pair
of upstanding spaced substantially parallel frame
webs, each of said webs having a continuous upper
portion extending to its upper end with holes
5: therein to provide bearing receiving openings,
each of said loomsides being cut away from the
upper end thereof to said openings to provide
passageways for shaft and bearing ingress into
said openings, a crank shaft unit for operating
10: the lay swords of the loom extending in said
openings crosswise of said loomsides and com-
prising two crank end sections and an inter-
mediate straight section coupled thereto and
bearings for said shaft supported on said loom-
15: sides and centered in said openings, said crank
shaft unit being adapted to be inserted into and

removed from said openings as a unit through said passageways.

7. In a loom, a frame structure comprising spaced loomsides, each provided with a continuous upper portion with a section of the continuous upper portion of each of said loomsides removed to provide an opening in communication with space above the upper end of its respective loomsides, a bearing mounting structure having an open ended key opening therein secured to the portions of each of said loomsides defining said first openings, a crank shaft unit for operating the lay swords of the loom extending in said key openings crosswise of said loom, and comprising two crank end sections and an intermediate straight section coupled thereto and bearings for said shaft, said bearings being secured to said bearing mounting structures respectively, said crank shaft unit being adapted to be inserted into and removed from said key openings through the first mentioned openings in said loomsides.

8. In a loom, a frame structure comprising spaced loomsides, each provided with a continuous upper portion interrupted by a transverse hole in open communication with the space above its respective loomsides, a bearing support structure attached to the sections of each of said loomsides defining its respective transverse hole, said bearing support structures having key openings therein, each with a circular base of more than 180° and a neck of reduced width extending

to the upper end of said bearing support structure to permit shaft ingress therein, a crank shaft for operating the lay swords extending in said openings crosswise of the loom, and having 5 straight shaft parts small enough in diameter to permit said shaft parts to be lowered through said necks into said circular bases of said openings respectively, and bearings for said shafts adapted to be slid axially along said shaft parts 10 into said openings for assembly and keyed into said openings against transverse removal.
